UNITED STATES PATENT OFFICE.

JOHN D. RAUCH, OF LIMA, OHIO, ASSIGNOR TO THE OHIO STEAM SHOVEL COMPANY,
OF LIMA, OHIO, A CORPORATION OF OHIO.

POWER SHOVEL.

Original application filed March 2, 1925, Serial No. 12,476. Patent No. 1,569,031, dated January 12, 1926.

Divided and this application filed July 29, 1925. Serial No. 48,708.

This invention relates to improvements in power shovels of the dipper type, and has for its principal object to provide a simple, durable and efficient mechanism for operating and controlling the dipper handle. The present application is a division of my prior application bearing Serial No. 12,476, filed Mar. 2, 1925, which has matured into Patent No. 1,569,031, granted Jan. 12, 1926. 10 The subject matter of the present application has been carved out of the said prior application.

The invention will best be understood by reference to the accompanying drawings, in which

Figure 1 is a general view in side elevation of the shovel.

Figure 2 is an enlarged detail view of the dipper operating mechanism.

20 Figure 3 is a detail view in vertical section of the friction devices of the dipper operating mechanism.

Figure 4 is a detail view of the dipper handle operating mechanism with parts shown in section; and

Figure 5 is a detail view in cross-section taken on line 5—5 of Figure 4.

Referring now to details shown in the drawings, my invention is illustrated as applied to a power shovel of the dipper type having the motor and main operating mechanism carried on a frame 1, which frame is pivotally mounted to swing on a vertical axis on a base 2. The base 2 is provided with propelling mechanism of any suitable form, herein consisting of an endless tread mechanism 3. The shovel 4 is of an ordinary dipper type having a handle 5 provided with a rack 6, engaging a pinion 7 carried on a boom 8, the latter being arranged at the front end of the main frame but so as to be raised or lowered by suitable draft means, such as a cable 10, suitably controlled from the main frame. The dipper 4 is further connected for operation by means of a single cable 11 passing over a sheave 12 on the upper end of the boom 8 and wound upon a main operating drum 13.

Referring more particularly to the subject-matter of the present invention which relates to the means for controlling the movement of the dipper handle 5, I provide a drum 90 arranged on a shaft 91 transversely of the front end of the main frame 1. A

clutch 93, of the usual friction type, is adapted to provide a driving engagement between the drum 90 and a gear 94 concentric therewith, this gear being driven through suitable driving connections (not shown) from the motor 20. The drum 90 is also provided with reverse driving connections comprising a gear 95 keyed on shaft 91 to rotate with the driving gear 94, as shown in detail in Figure 3. The gear 95 is meshed with a plurality of planetary gears 92—92 carried on a rotatable member 97. The outer peripheries of the planetary gears engage an internal gear 92^a on the drum member 96 integral with the drum 90.

A friction band 96^a engages the drum 96 to provide braking action thereon. A similar friction band 97^a restrains rotation of the planetary member 97 when it is desired to effectuate the driving connection through gears 92 in the usual manner, thus reversing the direction of rotation.

A pair of cables 99 and 99^a are wound upon the drum 90. The ends of said cables are suitably connected to said drum, as for instance by clips 99^b and 99^c, and said cables are wound in opposite directions from their connecting points, as will appear from Figures 4 and 5. The two cables extend forwardly and downwardly from the drum 90 and over idler pulleys 100 mounted on the boom 8 adjacent its point of pivotal connection with the frame 1 and from thence the cables extend upwardly and are wound about a drum 101 carried on the boom adjacent the pinion 7. The drum 101 is provided with a gear 102 thereon (see Figure 1) engaging a gear 103 which rotates the rack 6.

The cables 99 and 99^a are wound in reverse directions on the drum 101, in a manner which will hereinafter be more specifically described, but the general arrangement is such that by rotating the drum 90 in either direction the pinion 7 may be rotated so as to force the rack 6 and dipper handle 5 inward or outwardly as required. Furthermore the brake band 96^a may be operated so as to maintain the dipper handle in any desired position. Means are also provided for facilitating the initial adjustment of the cables 99 and 99^a in position and adjusting their tension upon the drums 90 and 101. In the form shown both of the drums are

provided with helical grooves in which the cables are wound. Referring now to the drum 101, which is best shown in cross-section in Figure 4 it will be seen that I 5 provide means whereby the drum body is split on a transverse plane so as to provide two portions 111 and 112 at opposite ends thereof. These portions are loosely mounted on sleeves 111^a and 112^a, respectively, both 10 being keyed to rotate as a unit with the shaft 98 and sleeves 111^a and 112^a. The sleeves 111^a and 112^a each have worm gears 113 at their outer ends, engaging the toothed periphery 113^a of the adjacent drum portion. 15 This arrangement permits either drum portion to be turned separately in either direction with respect to the shaft 98, by applying a crank of the usual kind on the squared end 113^b of either of the worms 113. 20 The ends of cables 99 and 99^a are connected respectively to the portions 111 and 112 and wound in opposite directions thereon.

Among the advantages of the construction above described is the provision of two 25 separate cables 99 and 99^a adapted to be wound in opposite directions upon the drums 90 and 101 but having their points of connection with drum 101 rotatable in either direction relative to each other by 30 means of the split drum connection above described. This arrangement permits ready replacement or repair of the cables connecting the two drums with far greater rapidity and facility than has heretofore been possible 35 when the connecting cables consisted of a single strand having its center portion wound around one of the drums, as for instance the drum 90, and with its two end portions connected to the other drum 101. 40 With two separately attachable cables 99 and 99^a each cable may be adjusted at opposite ends to the desired tension and number of turns desired on both drums independently of the other cable with far greater 45 ease and rapidity than the laborious operation of fitting and winding a single cable. Inasmuch as these cables are subject to considerable wear and frequent replacement, this feature presents a considerable saving 50 in time and labor. A further advantage of a two cable connection is that one cable may be replaced independently of the other when it begins to show wear, instead of requiring replacement of a double length of 55 cable.

A further advantage is the provision of independent adjustment means for the two ends of the cables on drum 101. It is manifestly desirable to maintain a constant tension on both of the cables 99 and 99^a during operation and at the same time maintain a substantially equal amount of cable upon the two drum portions 111 and 112 to repre-

sent approximately one-half the stroke of the dipper. Accordingly, with the double 65 adjustment illustrated herein, slack in either of the cables may be readily taken up and the proportion of cable on the two drum sections 111 and 112 may be readily readjusted whenever desired. 70

I claim:

1. In a device of the class described, a frame having a boom mounted thereon, a dipper provided with a handle, means on said boom for reciprocably moving said handle relative to said boom, a shaft having operative connection with said handle moving means, two drums mounted concentrically with said shaft, flexible cable actuating means including two cable portions each connected with one of said drums, means for independently rotating both of said drums with respect to said shaft, and locking means for connecting said drums in various adjusted positions. 80

2. In a device of the class described, a frame having a boom mounted thereon, a dipper provided with a handle, a rack on said handle having engagement with a pinion on said boom, a rotatable member having operative connection with said pinion, a pair of drums mounted concentrically with said rotatable member, flexible cable actuating means including two cable portions each connected with one of said drums, and means for positively rotating either of said drums respective to said rotatable member. 90

3. In a device of the class described, a frame having a boom mounted thereon, a dipper provided with a handle, means on said boom for reciprocably moving said handle relative to said boom, and including a rotatable member, a pair of drums mounted concentrically with said rotatable member, flexible cable actuating means including two cable portions each connected with one of said drums, and means for positively rotating either of said drums respective to said rotatable member comprising a self-locking worm gear connection between each of said drums and said rotatable member. 100

4. In a device of the class described, a frame having a boom mounted thereon, a dipper provided with a handle, means on said boom for reciprocably moving said handle relative to said boom, said means including a pair of drums having differential operative connection therewith, and flexible actuating means including a second drum mounted on the frame and two cable sections each independently connected at opposite ends between said last named drum and one of said pair of drums. 115

Signed at Lima, Ohio, this 17th day of July, 1925.

JOHN D. RAUCH.
